REFRIGERATION

Application filed October 7, 1930. Serial No. 486,929.

This invention relates to refrigerating apparatus of the compressor-condenser-expander type, and more particularly to a means for returning lubricant from the evaporator to the compressor in a flooded evaporator type system.

Due to the relatively low volatile nature of lubricants as compared to refrigerants, quantities of the former which are used to lubricate the compressor and are carried with the refrigerant to the evaporator remain therein and gradually accumulate until the efficiency of the system is seriously impaired. It is, therefore, necessary to provide some means for returning the lubricant from the evaporator to the compressor. An effective method of accomplishing this is to introduce the lubricant from the evaporator into the vapor suction line where it is drawn along with the refrigerant vapor back to the compressor.

This invention contemplates a means utilizing the boiling action of the refrigerant when it evaporates to effect the transfer of the lubricant into the vapor suction line where it can be drawn back into the compressor. A very satisfactory way to do this is by providing in the evaporator an inverted vessel enclosing an upwardly converging chamber which is open at the bottom below the normal liquid level in the evaporator and communicating at the top with the vapor suction line to the compressor. Bubbles resulting from the evaporation of the liquid refrigerant in the evaporator carry lubricant which may be floating on the surface of or mixed with the liquid refrigerant in the evaporator and due to the gradual reduction in area of the cross section of the upwardly converging chamber from the bottom thereof to the normal level of the liquid therein, there is an increased agitation and a distinct foaming at the surface of the fluid under the inverted vessel which results in lubricant bubbles being carried to the top of the chamber where they are drawn off through the vapor suction line.

This is more fully set forth in my co-pending application Serial Number 356,338, filed April 19, 1929, of which this case is a con-

tinuation in part. The present invention contemplates the provision of means whereby the heat of the incoming liquid refrigerant is utilized to increase the amount of ebullition of the liquid within the upwardly converging chamber under the inverted vessel thereby increasing the effectiveness of this method of lubricant return. This is of considerable importance when it is necessary or desirable to limit the size of the inverted vessel, as, for instance when the evaporator is of such small size or of such design that it is not adapted to receive an inverted vessel of sufficient size to allow the necessary decrease in cross sectional area from the bottom thereof to the liquid level therein to cause the rising vapor to gain such a velocity that there is created the requisite foaming at the surface.

This invention will be more readily understood by reference to the following description taken in connection with the accompanying drawing in which like reference characters indicate like parts.

In the drawing:

Fig. 1 is a vertical section of an evaporator of the flooded type in which is provided a lubricant return means contemplated by this invention;

Fig. 2 a plan view of the evaporator in Fig. 1 with part of the outer casing broken away; and

Fig. 3 a plan view of a slightly modified arrangement of the parts shown in Fig. 1.

Referring to Figures 1 and 2, an evaporator of the flooded type of any desired construction comprises a casing 10 with a portion 11 threaded at 12 or otherwise adapted to receive a closing member 13 through which extend refrigerant inlet conduit 14 and vapor suction line 15. Within the evaporator is an inverted vessel 16 enclosing an upwardly converging chamber 17 which is open at the bottom below the normal liquid level in the evaporator and communicates at its upper portion with vapor suction line 15 through conduit 18. An opening 19 in the vapor suction line 15 communicates with the vapor space above the normal liquid level in the evaporator to allow refrigerant vapor to be returned to the compressor.

Evaporation or boiling of the liquid refrigerant in the evaporator causes bubbles of refrigerant vapor to rise vertically through the accumulation of refrigerant and lubricant.

6 Due to the constantly decreasing cross sectional area of the chamber 17 from the bottom thereof to the surface of the liquid therein an excessive foaming is produced at said 10 surface due to the velocity of the upwardly rising bubbles when they reach the liquid surface within the chamber. The velocity of the upwardly rising vapor bubbles increases in the same ratio that the cross sectional area 15 decreases. For instance, the inverted vessel 16 may be substantially cone shaped as shown with the cross sectional area of chamber 17 at the liquid surface $\frac{1}{4}$ of the cross sectional area at the open bottom of the vessel. The 20 velocity of the vapor bubbles moving upwardly from the open bottom of the vessel will have increased four fold when they reach the surface of the liquid. Due to the surface tension of lubricant which is mixed with 25 the refrigerant or floating on the surface thereof each of the rapidly rising vapor bubbles takes on a thin film of the lubricant and due to the increased velocity, as explained above, a violent foaming occurs at the surface of the liquid. The foam comprises a 30 myriad of small bubbles each composed of a lubricant film envelope filled with refrigerant vapor.

When the lubricant is broken up into a 35 great number of minute films the specific gravity of the mass of lubricant thus broken up is greatly reduced. Due to this reduction in the specific gravity of the lubricant and the difference in pressure between the 40 vapor suction line and the upwardly converging chamber, and also due to the velocity with which they leave the surface of the liquid, the bubbles are carried to the top of chamber 17 where the lubricant and refrigerant vapor are drawn off through conduit 18 45 and the vapor suction line 15 and returned to the compressor.

Liquid refrigerant is supplied to the evaporator through conduit 20 which may be in 50 the form of a capillary tube as shown for regulating the supply to the evaporator to maintain the liquid level therein substantially constant. To give conduit 20 sufficient length it may be coiled at 21 before discharging 55 into the evaporator at 14.

If the cone shaped or upwardly tapering member 16 is not of sufficient size, that is, if the decrease in cross sectional area from the bottom thereof to the normal liquid level in 60 the evaporator is not great enough, there will not be sufficient foaming of the liquid refrigerant in chamber 17, under certain operating conditions, to carry the lubricant to the top.

To create sufficient ebullition of the liquid refrigerant in chamber 17 in such instance,

the refrigerant inlet conduit 20 is positioned adjacent to or within the vapor suction line 15, and extended into the evaporator where it is welded to or otherwise placed in good thermal conductive relation with 70 the inverted vessel 16 as at 22. Conduit 20 is then given a number of turns either on the outside of the evaporator, as shown in Fig. 1, or around the vapor suction line within the evaporator, as shown at 23 in Fig. 3, to 75 give it sufficient length before it discharges into the evaporator at 14. The coil in conduit 20 is placed immediately before the discharge point 14 and not between the thermal contact 80 and the source of refrigerant supply since there is a falling temperature gradient from the source of supply to the discharge point in the evaporator and it is desirable to obtain as much heat as possible from the incoming liquid refrigerant for heating the liquid under the inverted vessel. 85

With this construction the liquid refrigerant conduit is in good thermal relation with both the vapor suction line and the inverted vessel 16, and the heat of the incoming liquid refrigerant is utilized to produce greater evaporation of the refrigerant in chamber 17, and also to vaporize any liquid refrigerant which may be carried over into the vapor suction line. 90

It is, of course, not necessary to use a capillary tube for controlling the liquid refrigerant delivered to the evaporator but any well known means such as a float valve may be substituted, in which case the liquid refrigerant conduit 20 would be connected to an inlet valve and the outlet from such valve would be extended into thermal exchange relation to the liquid in the upwardly converging chamber. 100

It will be obvious to those skilled in the art that various other changes may be made in the construction and arrangement without departing from the spirit of the invention and therefore the invention is not limited to what is shown in the drawing and described in the specification but only as indicated in the appended claims. 110

I claim:

1. The method of circulating lubricant in 115 a refrigerating system which comprises applying the specific heat of condensed refrigerant to boil a body of liquid refrigerant with lubricant therein to form bubbles of refrigerant vapor in said body, constricting the upward path of flow of a vapor bubbles in said body to foam the lubricant and removing the lubricant foam from the presence of said body. 120

2. The method of circulating lubricant in 125 a refrigerating system which comprises applying the specific heat of condenser refrigerant to boil a body of liquid refrigerant with lubricant therein to form bubbles of refrigerant vapor in said body and gradually con-

- stricting the upward path of flow of said bubbles to increase the velocity thereof, which foams the lubricant, and removing the lubricant foam from the presence of said body.
- 5 3. The method of circulating lubricant in a refrigerating system of the compressor-condenser-evaporator type in which is contained a mixture of refrigerant and lubricant which comprises maintaining an appreciable quantity of liquid refrigerant and some lubricant in the evaporator, applying the specific heat of liquid refrigerant from the condenser to boil liquid refrigerant in the evaporator, constricting the upward passage of vapor bubbles in the boiling refrigerant to produce a lubricant foam, removing the foam from the evaporator and delivering said foam to the compressor.
- 10 4. In a refrigerating system of the compressor-condenser-expander type, means for returning lubricant from the evaporator to the compressor comprising an inverted vessel enclosing an upwardly converging chamber open at the bottom below the normal liquid level in the evaporator and communicating at the top with the vapor suction line, an evaporator refrigerant inlet conduit in thermal conductive relation with said inverted vessel.
- 15 5. In a refrigerating system, an evaporator adapted to contain a quantity of liquid refrigerant and lubricant, means for maintaining a substantially constant liquid level within said evaporator, an inverted vessel within said evaporator, said vessel having an upwardly converging chamber therein open at the bottom below the normal liquid level in said evaporator and communicating at the top with a vapor suction line and means for applying the specific heat of the incoming liquid refrigerant to said inverted vessel.
- 20 6. In a refrigerating system, an evaporator including a header, a supply of liquid refrigerant for said evaporator, means for maintaining the liquid level in said header substantially constant, an inverted vessel within said header, said vessel having an upwardly converging chamber open at the bottom below the normal liquid level in said header and communicating at the top with a vapor suction line and means for applying the specific heat of said refrigerant supply to said inverted vessel.
- 25 7. In a refrigerating system of the compressor-condenser-expander type, in combination, an evaporator, means for maintaining a substantially constant fluid level in said evaporator, an inverted vessel within said evaporator, said vessel having an upwardly converging chamber open at the bottom below the normal liquid level in the evaporator, a vapor suction line extending into said evaporator and communicating with the vapor space in said evaporator and the top of said
- chamber, and a refrigerant supply line extending into said evaporator in thermal conductive relation with said inverted vessel.
- In testimony whereof I affix my signature.
